WALL PANEL FOR FURNACE JACKETS
OR THE LIKEAllen P. Livar, Dayton, Ohio, assignor to Chrysler
Corporation, Detroit, Mich., a corporation of
Delaware

Application April 6, 1942, Serial No. 437,800

6 Claims. (Cl. 189—34)

My present invention relates to the construction of wall panels for furnace jackets or the like, the invention being such as to be of greatest utility for insulating heat radiating bodies, such as furnaces, boilers, water heaters, or other similar devices, but being adaptable to the formation of jackets for other types of equipment, such as air conditioner cabinets, storage cabinets, and the like. In other words, the invention is of general utility but with one or two preferred applications. 10

The problems to be solved in the formation of furnace jackets for warm air furnaces are many and complex, especially in connection with the present low cost housing projects due to the scarcity of certain materials. In low cost housing projects, space is definitely at a premium and a furnace jacket must be capable of preventing excessive radiation from an excessively heated furnace body to closely adjacent walls, such as the walls of a utility closet, without using the large air gaps or certain materials heretofore found necessary. In other words, where ordinarily a furnace body may be spaced four or five inches from the jacket wall and the instructions for use of the furnace may state that the jacket wall should be spaced a minimum of ten to twelve inches from the nearest building wall, governmental bodies at the present time specify a certain size of closet in which a furnace of a specified capacity is to be installed, these specifications usually meaning that the furnace body may be spaced only two or three inches from the jacket wall and the jacket wall only two or three inches from the closet wall. It is, therefore, imperative that a highly efficient form of insulation for the jacket be devised. It is a primary object of the present invention to provide a furnace jacket which can meet the minimum space and maximum heat specifications of small dwellings of the nature described above.

It is the secondary object of the present invention to provide a jacket of maximum efficiency which can be used to insulate any body, either to confine heat within the jacket or to prevent heat from penetrating into the jacket.

Another object of the present invention is to provide an insulating jacket which may be formed of a variety of materials, such materials being readily available.

A further object of the present invention is to provide an insulating jacket which may be quickly assembled at the point of use from a plurality of previously formed panels with a minimum of effort on the part of the assembly crew.

A further object of the present invention is to

provide a panel adapted to form a portion of a jacket, which panel is quickly assembled without the use of the multitude of screws or other separable fasteners heretofore used in panel assemblies, the separable fastening means required for the present invention being limited to one ordinary screw.

A further object of the present invention is to provide a jacket panel which may be assembled in much less time than any previously known jacket panel, thereby reducing the cost of equipment for low cost housing projects.

The foregoing and other objects and advantages of the present invention may be more readily ascertained from the following specification taken in connection with the accompanying drawing wherein like numerals refer to like parts throughout.

In the drawing,

Fig. 1 is a view in perspective, with parts broken away, of a furnace utilizing the present invention;

Fig. 2 is a horizontal cross-section taken substantially along line 2—2 of Fig. 1;

Fig. 3 is a vertical section of a single panel taken substantially along line 3—3 of Fig. 1;

Fig. 4 is a detail section taken substantially along line 4—4 of Fig. 3;

Fig. 5 is a detail section showing an enlargement of the portion of Fig. 2 encircled in the circle marked 5; and

Fig. 6 is a sectional view taken through one of the panels forming the jacket, in substantially the plane of Fig. 2, this figure showing the method of assembling the panel-forming members.

The present invention comprises a plurality of jacket panels 10 which may differ in configuration in order to provide for such members as the mounting panel 11 and inspection door 12 of a furnace, but which are otherwise substantially

40 duplicates in detail. A plurality of such panels may be united at their edges to form a furnace jacket as shown or to form the jacket of any other type of equipment. In the illustration the furnace jacket surrounds a furnace body 13 in

45 which is enclosed a vaporizing burner 14 having oil admitted thereto through tube 15 from the float valve 16, and the furnace is provided with a blower 17 for supplying forced draft to the burner 14. The details of the furnace body and other equipment are nonessential, such members being shown only for purposes of illustration.

Each of the jacket panels 10 comprises an outer metallic sheet 20 of relatively heavy gauge, such as 16 gauge metal, so as to form a rela-

tively rigid, form-sustaining outer surface upon which may be applied a layer of paint for decorative purposes. Each panel likewise comprises a thin inner metallic sheet 21 formed of relatively light gauge metal, such as 22 gauge or 24 gauge, the metal being sufficiently resilient that it may be bowed easily but will tend to spring back to a flat plane when released. Both sheets may be formed of ordinary terne-plate or "black iron," as distinguished from previously prescribed sheets of special alloy characteristics.

The outer plate 20 has retaining means extending along each vertical edge portion of one surface of the sheet, these retaining means preferably comprising a Z-bar 22 having one leg 23 fastened to the outer sheet as shown at the left side of Fig. 5, or to members likewise fastened to the outer sheet 20 as shown at the right side of Fig. 5. In either case the members 22 are united to the outer sheet 20 and have a free edge portion 24 formed by the outer leg of the Z-bar spaced from the surface of the sheet 20, lying in a plane parallel thereto, and pointing toward the vertical centerline of the sheet so that the retainer members provide inwardly facing open channels extending vertically along the outer edges of the sheets. Each of the retainer members 22 is preferably in the shape of a Z-bar, but other shapes may be used as will be obvious to the skilled metal worker.

Each of the inner metal plates 21 is provided with clip members 25 extending along the vertical edges thereof in position to engage the portions 24 of the retainer members 22 when the inner and outer sheets are assembled to lie in parallel planes. The clip members 25 are preferably in the form of shallow Z-bars having one leg 26 fastened to the surface of the sheet 21 and the free leg 27 narrowly spaced from, and lying in a plane horizontal to, the sheet 21 so as to provide narrow outwardly facing open channels of sufficient depth firmly to grip the edge portions 24. A plurality of such clip members may be used although for convenience of assembly a single continuous bar, which likewise acts as a stiffening member for the sheet 21, is preferred. Similarly, the Z-bars 22 are preferably continuous to act as frame members for the jacket.

The inner and outer sheets may be assembled as shown in Fig. 6 by bowing the inner sheet about its vertical centerline to permit engagement of the retainer members and clip members. Pressure at the centerline of the inner sheet may then force the inner sheet toward the outer sheet and force the clip members to grip the retainer members, the inner sheet being preferably sufficiently resilient to assume a plane parallel to the outer sheet.

The inner sheet is preferably stiffened by fastening a Z-bar 30 along its vertical centerline. The depth of the Z-bar is such as to space the inner and outer sheets in parallel planes. Other forms of bar members may be used, but it is preferred to use a Z-bar since stock used to form the Z-bars 22 may be used to form the Z-bars 30, thus eliminating a special forming operation.

As shown in Figs. 2 and 5 alternate panels 19 may be provided at their extreme edges with panel assembling means, such as provided by the Z-bar 31 comprising a leg 32 fastened between the leg 23 and the outer sheet sheet 20 and a free leg 33 extending to the extreme edge of the sheet 20 to provide an outwardly facing narrow channel adapted to engage the end edge 34 of the next adjacent panel 10. As shown in

the illustration, the end edge 34 is bent at right angles to the plane of the sheet so as to provide a corner assembly, but it is to be realized that the same construction could be used to provide a longer wall consisting of panels assembled in line with each other. The inner sheets 21 are preferably dimensioned so that their extreme edges substantially abut to form an enclosed vertically extending air space 35 outside of the retainer members 22. Likewise, enclosed air spaces 36 are provided inside of the retainer members 22. The air spaces afford efficient insulation in addition to the reflecting capacity of the inner sheet 21.

15 The panel members described may be complete for the purpose under consideration, but for high temperatures such as generated by a warm air furnace body further insulation may be necessary, in which case a relatively rigid self-sustaining plaque 40 of insulating material may be slid longitudinally of the sheet 20 with its vertical edges loosely embraced in the channels formed by the retainer members 22. In high temperature applications the plaque 40 preferably comprises a body 41 of insulating material such as asbestos, agglomerated vermiculite, or the like, and a reflecting sheet 42 of aluminum foil or the like. Other types of material, either alone or in laminated layers, may be substituted therefor in accordance with the temperature, the materials available, and the purpose to which the panel is to be put as is well-known in the arts.

35 In order to support the inner sheet 21 and the insulating plaque 40 (if used) vertically of the outer sheet 20, the outer sheet 20 is provided with a bottom retaining member 45 preferably in the form of a Z-bar having one leg 46 fastened to the outer sheet 20 and its free leg 47 lying parallel to and spaced from the outer sheet 20 to form an upwardly facing open channel of sufficient depth to embrace the outer panel 20. The Z-bar is of relatively rigid construction so as to sustain the weight thus imposed upon it and to eliminate the necessity for fastening the inner and outer sheets to each other or adhering or fastening of the insulating plaque to the outer sheet. The Z-bar 45 may extend entirely across the width of the panel so as to prevent air movement through the air spaces 35 and 36 in low temperature installations, but in high temperature installations, such as furnace and boiler jackets, it is preferably of narrow width and placed at the vertical centerline so as to permit relatively unconfined and rapid flow of cooling airstreams through the spaces 35 and 36.

55 In order to lock the assembly against accidental displacement, there is preferably provided a locking member 50 of deformable material, such as 30 gauge metal, which has one end 51 fastened to the top of the outer sheet 20 at such a height as to be just above the upper edges of the insulating plaque 40 and the inner sheet 21 when they rest upon the bottom retainer member 45. The locking member 50 may be bent to the dotted line positions to permit assembly and then deformed around the upper edge of the sheets as shown in Fig. 3. Preferably, the extreme end 52 of the locking member is fastened to the top of the inner sheet 21 as by means of a sheet metal screw 53. The locking member is preferably positioned adjacent the upper end of the spacer member 30 so that, when the sheet metal screw 53 is applied,

a rigid self-sustaining panel which cannot be accidentally disarranged is provided.

When the insulating plaque 40 is utilized, the spacer bar 38 is preferably of such depth as to press the central portion of the insulating plaque against the outer sheet. The edges of the insulating plaque preferably extend so as to lie adjacent the legs 27 of the retaining clips 25 which thus prevent the insulating plaque from coming in contact with the inner sheet 21 at any point.

While I have illustrated all metal members of each sub-assembly as being spot-welded to each other, it is obvious that other fastening means may be utilized for forming the sub-assemblies, spot-welding being merely the most economical and rapid method of forming the sub-assemblies.

Having illustrated and described the preferred embodiment of my invention, it should be apparent to those skilled in the art that the same permits of various modifications in arrangement and detail. All such modifications as come within the scope of the following claims are considered a part of my invention.

I claim:

1. A panel for forming a vertical wall of a furnace jacket or the like comprising a relatively rigid outer metal sheet, a retainer bar fastened longitudinally of each vertical edge portion of said sheet with an edge portion of each bar spaced from and lying substantially parallel to said sheet, each of said edge portions of said retainer bars extending toward the central portion of said sheet whereby said retainer bars form opposed open channels, a relatively rigid plaque of insulating material of lesser thickness than the depth of said channels and having its vertical edges loosely retained in said channels, a relatively resilient inner metal sheet having clip members extending along each vertical edge portion thereof in position to engage said edge portions of said retainer bars when said inner and outer metal sheets are assembled to lie in parallel planes, and a spacer bar extending longitudinally of one of said sheets substantially at the vertical centerline thereof, said inner sheet being sufficiently resilient that it may be bowed about said spacer bar to permit engagement of said clip members with said retainer bars.

2. A panel for forming a vertical wall of a furnace jacket or the like comprising a relatively rigid outer metal sheet, a retainer bar fastened longitudinally of each vertical edge portion of said sheet with an edge portion of each bar spaced from and lying substantially parallel to said sheet, each of said edge portions of said retainer bars extending toward the central portion of said sheet whereby said retainer bars form opposed open channels, a relatively rigid plaque of insulating material of lesser thickness than the depth of said channels and having its vertical edges loosely retained in said channels, a relatively resilient inner metal sheet having clip members extending along each vertical edge portion thereof in position to engage said edge portions of said retainer bars when said inner and outer metal sheets are assembled to lie in parallel planes, and spacer means fastened to the surface of said inner sheet and engageable with said plaque to force said plaque against said outer sheet.

3. A panel for forming a vertical wall of a furnace jacket or the like comprising a relatively rigid outer metal sheet, a retainer bar fastened longitudinally of each vertical edge portion of

said sheet with an edge portion of each bar spaced from and lying substantially parallel to said sheet, each of said edge portions of said retainer bars extending toward the central portion of said sheet whereby said retainer bars form opposed open channels, a relatively rigid plaque of insulating material of lesser thickness than the depth of said channels and having its vertical edges loosely retained in said channels, a relatively resilient inner metal sheet having clip members extending along each vertical edge portion thereof in position to engage said edge portions of said retainer bars when said inner and outer metal sheets are assembled to lie in parallel planes, and spacer means fastened to the surface of said inner sheet and engageable with said plaque to force said plaque against said outer sheet comprising a relatively rigid bar extending substantially along the vertical centerline of said inner sheet.

4. A panel for forming a vertical wall of a furnace jacket or the like comprising a relatively rigid outer metal sheet, a retainer bar fastened longitudinally of each vertical edge portion of said sheet with an edge portion of each bar spaced from and lying substantially parallel to said sheet, each of said edge portions of said retainer bars extending toward the central portion of said sheet whereby said retainer bars form opposed open channels, a relatively rigid plaque of insulating material of lesser thickness than the depth of said channels and having its vertical edges loosely retained in said channels, a relatively resilient inner metal sheet having clip members extending along each vertical edge portion thereof in position to engage said edge portions of said retainer bars when said inner and outer metal sheets are assembled to lie in parallel planes, spacer means fastened to the surface of said inner sheet and engageable with said plaque to force said plaque against said outer sheet, and a bottom retainer member comprising a relatively rigid clip carried by said outer sheet and adapted to embrace the lower edges of said plaque and said inner sheet.

5. A panel for forming a vertical wall of a furnace jacket or the like comprising a relatively rigid outer metal sheet, a retainer bar fastened longitudinally of each vertical edge portion of said sheet with an edge portion of each bar spaced from and lying substantially parallel to said sheet, each of said edge portions of said retainer bars extending toward the central portion of said sheet whereby said retainer bars form opposed open channels, a relatively rigid plaque of insulating material of lesser thickness than the depth of said channels and having its vertical edges loosely retained in said channels, a relatively resilient inner metal sheet having clip members extending along each vertical edge portion thereof in position to engage said edge portions of said retainer bars when said inner and outer metal sheets are assembled to lie in parallel planes, spacer means fastened to the surface of said inner sheet and engageable with said plaque to force said plaque against said outer sheet, a bottom retainer member comprising a relatively rigid clip carried by said outer sheet and adapted to embrace the lower edges of said plaque and said inner sheet, and a locking member comprising a deformable clip carried by said outer sheet and adapted to be formed around the upper edges of said plaque and said inner sheet.

6. A panel for forming a vertical wall of a fur-

nace jacket or the like comprising a relatively rigid outer metal sheet, a retainer bar fastened longitudinally of each vertical edge portion of said sheet with an edge portion of each bar spaced from and lying substantially parallel to said sheet, each of said edge portions of said retainer bars extending toward the central portion of said sheet whereby said retainer bars form opposed open channels, a relatively rigid plaque of insulating material of lesser thickness than the depth of said channels and having its vertical edges loosely retained in said channels, a relatively resilient inner metal sheet having clip members extending along each vertical edge portion thereof in position to engage said edge por-

tions of said retainer bars when said inner and outer metal sheets are assembled to lie in parallel planes, spacer means fastened to the surface of said inner sheet and engageable with said plaque to force said plaque against said outer sheet, a bottom retainer member comprising a relatively rigid clip carried by said outer sheet and adapted to embrace the lower edges of said plaque and said inner sheet, a locking member comprising a deformable clip carried by said outer sheet and adapted to be formed around the upper edges of said plaque and said inner sheet, and means to fasten said locking member to the top of said inner sheet.

ALLEN P. LIVAR.
